UNITED STATES PATENT OFFICE

2,557,106

HIGH-PRESSURE OIL NOZZLE FOR
GRINDINGS

Francis B. Hughes, Washington, D. C.

Application April 12, 1946, Serial No. 661,638

4 Claims. (Cl. 299—145)

(Granted under the act of March 3, 1883, as
amended April 30, 1928; 370 O. G. 757)

1

This invention relates to nozzles, and more particularly to an antisplash nozzle which is designed to control the application of the cooling and lubricating media used in cooperation with grinding and cutting tools.

In the prior practices of cutting and grinding on automatic machine tools, difficulty has been experienced in processing hard or large pieces of work due to the overheating which resulted from the inability of the heat transfer media or lubricant to penetrate the area of contact and thereby decrease the generation of heat, and prevent the "loading" of the grinding wheel. This deficiency in the process resulted in a breakdown of the grinding wheels or cutting tools, the burnishing of the work in process, as well as, a general slowing-up of the cutting or grinding operations. While an increase of the cooling oil pressure would have remedied this problem, the excessive splashing which bounced off the work in process could not be controlled, and resulted in an impractical messy operation even with shields.

By the practice of my invention, the speed of the cutting and grinding operations may be substantially increased without experiencing the deleterious effects of the burnishing of the work, of the splashing of the lubricants and/or cooling media and of the accompanying break-down of the grinding wheels or cutting tools. In other words, the burnishing of the work in process is substantially eliminated and the life of the grinding wheels or cutting tools is extended three or four times the present life. Further, any material splashing of the lubricants and/or cooling media is abolished, coupled with an overall reduction in the amount of said lubricants and/or cooling media that may be required to process the hardened work or material.

It is an object of this invention to provide a nozzle for grinding and cutting operations which is so constructed as to adjustably enable the projection of a pressure jet of cooling oil or other media to the exact point of tangential contact between the cutting tool or grinding wheel and the work to be processed.

Another object of the invention is to provide a combination nozzle having an adjustable exterior sleeve so designed as to permit and to regulate a complete circular collar or curtain of oil to be projected about the main jet of cooling oil or other media.

Another object of the present invention is to provide an antisplash nozzle of the above described type producing a primary stream of fluid

and a secondary flow of said fluid in the form of a curtain about said primary stream, wherein the direction of stream flow is adjustable with respect to the direction of curtain flow.

5 Another object of the present invention is to provide an antisplash nozzle of the above described type producing a central high velocity primary fluid flow and a low velocity secondary fluid curtain flow surrounding said primary flow.

10 A still further object of the invention is to provide an inexpensive adjustable nozzle which may be attached to any feed line which, in prior practices, has provided the grinding and cutting machines with the required cooling oil or other media.

These and other objects will be apparent from a study of the appended specification, which is presented by way of exemplification, and is not meant to limit the invention. In the drawings:

20 Fig. 1 is an exploded isometric view of the nozzle showing the component parts thereof; and Fig. 2 is a longitudinal section of the nozzle showing the component parts thereof in assembled position.

25 Referring to the drawings, the present nozzle is provided with an exterior sleeve 12, the rear or base portion of which is adapted with internal female threads 20 for adjustably mounting the same on the seat 16. The seat 16 is provided with

30 two portions formed integral with each other: one portion thereof is the coupling 40 provided with the external threads 26, cooperating with the internal threads 20 of sleeve 12 for adjustably mounting the latter; and the passageway 50 there-through having a partially threaded portion 22 for coupling the entire nozzle to a cooling medium feed line or the like, not shown; and the other portion is a socket 23 shaped to provide an interior sleeve juxtaposed with the substantially

35 coextensive forward portion 13 of the exterior sleeve 12 to form an annular by-pass 30 therebetween. By adjusting the position of the exterior sleeve 12 on the seat 16 the space 21, or the area of the openings of channels 28, may be varied by

40 cooperation between the shoulder 34 formed on the exterior sleeve 12 and the flange 34a formed on the interior sleeve, or by partially covering said openings by the face 55 on sleeve 12, thereby controlling the amount of fluid flow through said by-pass, as will become more fully understood from the following discussion.

45 The socket portion 23 of the seat 16 is internally adapted to receive a spherical nozzle stem mounting member 24, universally adjustable 50 therein, carrying the elongated tubular stem 18,

the coupling portion 40 of seat 16, through its passage 50, and stem 18 combining to form a central main duct through said nozzle. In addition, the socket portion 23 is provided with an internally threaded portion 25 adapted to receive the annular clamping and retaining member 17 having the external threads 32, which cooperates with the socket 23 to hold the spherical nozzle stem mounting member 24 in the desired position, tightening thereof against the mounting member 24 being accomplished by aid of a spanner wrench (not shown) and the wrench sockets 19.

The coupling portion 40 of the seat 16 is further provided at its socket adjacent end with the above-mentioned radial channels 28, connecting the passage 50 with the space 21 and the annular by-pass 30. The central main duct formed by the coupling 40 and the stem 18 enables a central main flow of cooling oil or other fluid medium, entering the nozzle through the passageway 50 and being emitted as a primary stream flow from the forward discharge end 51 of the stem 18, while the channels 28 enable a portion of this fluid to be disbursed into the adjustable space 21 to form a secondary by-pass flow being emitted from the annular by-pass 30 as a circular collar or curtain about the primary stream of cooling medium. It will now be appreciated that by suitable adjustment of the sleeve 12 on seat 16 one may control the fluid flow through the by-pass 30, by the above-mentioned regulation of the openings of the channels 28, or of the space 21, and thus control the velocity of the circular collar or curtain of fluid issuing therefrom substantially independent of the main stream flow.

In assembling the present nozzle, the seat 16 is threaded into the exterior sleeve 12, the stem carrying mounting 24 is placed in the socket portion 23 of the seat, and the clamping and retaining member 17 is threaded into said socket. In the operation of the nozzle, it is mounted or attached to a conventional cooling oil feed line by means of the threaded portion 22 of the seat 16. Its assembly allows a high pressure primary flow of the oil or cooling medium from the feed line to pass into and through the main duct formed by the coupling 40 and the stem 18 and to be emitted therefrom as a main stream, while a secondary portion of the lubricant or cooling medium passes through the channels 28 into space 21, and thence through the annular curtain forming by-pass 30. When so by-passed, this fluid is emitted from the nozzle in the form of a curtain or collar about the main flow of oil or other cooling medium. The desired curtain flow velocity is obtained by adjustment of sleeve 12 on seat 16 to vary the size of space 21, or the openings of the channels 28. The independent control of the curtain flow thus afforded enables an accurate adjustment of the nozzle 18 to insure proper impingement of the main stream flow upon the cutting or grinding interface, and ready observation thereof. To this end, the curtain flow may be stopped by closing space 21, or the openings of the channels 28, thus enabling ready accessibility of the clamping member 17 to permit proper adjustment of the stem 18 through its universal mounting. Once adjusted the clamping member 17 is tightened against the stem mounting 24 to fix it in adjusted position, the curtain flow is established by permitting flow through the channels 28 by varying the position of the curtain forming and controlling sleeve 12, and the desired curtain flow characteristics

are obtained by proper adjustment thereof to substantially quench the splashing resulting from the main stream flow. Thus when the nozzle is properly installed on the fluid feed line, it provides an unimpeded central main flow of lubricant passing through the nozzle and being projected on to the exact point of tangential contact between the cutting or grinding tool and the work to be processed, and a secondary flow passing through the curtain by-pass to form a curtain or collar of fluid about the main stream of fluid emitted from the nozzle stem 18, substantially quenching the splashing resulting from the impingement of the stream upon the cutting or grinding interface.

By use of the nozzle embodying the present invention, cutting and grinding operations may be conveniently accomplished at a higher rate of speed than heretofore, due to the fact that they may be practically performed with the exact point of machining contact immersed in a bath of heat transfer fluid which is so controlled as to substantially eliminate the splashing effect that heretofore has necessitated the use of cumbersome shields or resulted in an excessive messiness about the equipment. The controlled projection of the heat transfer fluid on the work, without the attendant splashing, has served to transfer the frictional heat to such an extent as to substantially eliminate the burnishing of the work. In addition, the projected fluid at the increased working pressures, which serves to clean or wash the grinding wheel or cutting tool employed, has increased the life thereof three fold. Therefore, through the use of my invention, a better product may be manufactured with greater economy, convenience, and facility.

If desired, various sized stems 18 may be provided to enable the application of the proper amount of oil flow to the exact interface between the cutting tool or grinding wheel and the work to be processed. Also, the shape of the outlet port or orifice 51 of stem 18 may likewise be varied to enhance the desired results. Other variations and modifications of the present invention, within the spirit and scope thereof as defined by the appended claims, will be apparent to those skilled in the art and are within the monopoly here embraced.

The invention herein described may be manufactured and used by or for the Government of the United States of America for governmental purposes without the payment of any royalties thereon or therefor.

Having thus described my invention, I claim:

1. A nozzle for directing a liquid medium upon a cutting or grinding interface comprising a stem for directing a stream of said medium, a mounting therefor, a socket for said mounting, a clamping means, said stem and mounting being adjustable in said socket and being clamped in adjusted position by said clamping means, a coupling integral with said socket and having a passageway therethrough, said passageway and stem forming a main duct, and a liquid by-pass forming sleeve adjustably mounted on said coupling and socket, said sleeve being spaced from said socket along a portion of said socket to form an annular curtain generating by-pass to provide a curtain of said medium about said stream, said main duct and by-pass being connected by a channel, said sleeve by its adjustability controlling said curtain substantially independently of said stream by regulation of the egress of liquid from the channel.

2. A nozzle for directing a cooling and lubricating medium upon a cutting or grinding interface comprising a stem for directing a stream of said medium, a mounting for said stem, a seat for said mounting having a passageway therethrough, said mounting and stem being adjustable in said seat, a clamping member to clamp said mounting and stem in adjusted position, said passageway and stem forming a main duct, and a liquid by-pass forming sleeve adjustably mounted on said seat and spaced therefrom along a portion of said seat to form a curtain generating by-pass providing a curtain flow about said stream, said duct and by-pass being connected by a channel, the egress of liquid from said channel being varied by adjustment of said sleeve to control the curtain flow substantially independently of said stream.

3. An antisplash nozzle for liquid media comprising a stem for directing a stream of said medium, a mounting for said stem, a seat for said mounting having a passageway therethrough, said mounting and stem being adjustable in said seat, means for clamping said mounting and stem in adjusted position, said stem and passageway forming a main duct, and a liquid by-pass forming sleeve adjustably mounted on said seat and spaced therefrom along a portion of said seat to form a curtain generating by-pass providing a curtain flow about said stream, said duct and by-pass being connected by a channel, the egress of liquid from said channel being varied by adjustment of said sleeve to control the curtain flow.

4. An antisplash nozzle for liquid media comprising a stem for directing a stream of said medium, a mounting therefor, a seat for said mounting having a passageway therethrough,

said stem and mounting being adjustable in said seat, said passageway and stem forming a main duct, and a by-pass forming sleeve adjustably mounted on said seat and being spaced therefrom along a portion of said seat to form a curtain by-pass providing a curtain flow about said stream, said duct and by-pass being connected by a channel, liquid flow through said channel being varied by adjustment of said sleeve to control the curtain flow.
